E. LAAS.
RAIL ANCHOR.
APPLICATION FILED MAY 17, 1915.

1,170,500

Patented Feb. 1, 1916.

UNITED STATES PATENT OFFICE.

EDWARD LAAS, OF CHICAGO, ILLINOIS, ASSIGNOR TO OTTO R. BARNETT, OF CHICAGO, ILLINOIS.

RAIL-ANCHOR.

1,170,500.

Specification of Letters Patent. Patented Feb. 1, 1916.

Application filed May 17, 1915. Serial No. 28,662.

To all whom it may concern:

Be it known that I, EDWARD LAAS, a citizen of the United States, residing at Chicago, in the county of Cook and State of Illinois, have invented certain new and useful Improvements in Rail-Anchors, of which the following is a specification.

My invention relates to a rail anchor or anti-creep and particularly to a rail anchor of the wedge type, that is to say, of the type employing a wedging engagement between the relatively movable elements of the device for producing the binding or gripping action of the device on the rail; and the principal object of the invention is to provide novel and effective means for absorbing vibration between the elements of the device having said wedging engagement and preventing a retrograde movement of one element with respect to the other, which movement, if unchecked, would necessarily impair or destroy the hold of the device on the rail.

With this object in view, the invention consists of the novel arrangements and devices relating or applicable to rail anchors which will be hereinafter described and claimed.

The invention is illustrated, in certain preferred embodiments, in the accompanying drawings wherein—

Figure 1 is a plan view of a rail anchor constructed in accordance with my invention and shown as applied to a rail; certain parts of the anchor being shown in section. Fig. 2 is a vertical sectional view taken on line 2—2 of Fig. 1. Fig. 3 is a detail view of the elastic element employed for absorbing vibration and preventing retrograde movement of the wedge. Fig. 4 is a section on line 4—4 of Fig. 3.

Like characters of reference designate like parts in the several figures of the drawings.

In the drawings, A designates a rail, and B one of the cross ties on which the rail is laid.

The rail anchor consists of two members C and D which have a wedging relation with respect to each other and together provide means for engaging the base flange E of the rail. The precise construction of the members of the rail anchor might be varied considerably. For the purpose of illustrating the principle of my invention I have

shown the same as embodied in a rail anchor which in other respects is of common type.

The member A is composed of a bar 10 which extends under the base flange of the rail and is formed in one end with a jaw 11 extending around one edge of the base flange, and on the other end with a larger jaw 12 which is provided with a flange 13 adapted to bear against the tie B. The member D is wedge-shaped and driven into jaw 12 between said jaw and the base flange of the rail. Preferably the member D is formed with a groove 14 which embraces the edge of the base flange of the rail. The opposite vertical surface 15 of the wedge bears against the inner vertical face 16 of the jaw 12. The latter is formed with a recess 17 in which is seated a curved or arcuate spring 18 (Figs. 3 and 4,) the ends 19, 20 of which are preferably beveled and overlap each other. When the wedge is driven into jaw 12 toward the tie B the spring 18 is compressed, that is, its diameter is considerably reduced. It, therefore, exerts a pressure against the wedge D which helps to maintain the intimate wedging relation between the members of the rail anchor and the base flange of the rail by absorbing vibration and checking the tendency of the wedge to back out of the jaw. The member C of the anchor is preferably reinforced by a strengthening rib 21.

The jaw 11, it will be seen, stands out of contact with the tie B. Therefore with the traffic passing over the rails in the direction 90 toward tie B any tendency of the rail to creep will cause the device to be cramped on the rail. The creeping tendency is, therefore, self-checked provided the initial grip of the anchor on the rail be sufficiently intimate so that any movement of the rail is imparted to the free end of the anchor, that is, the end provided with jaw 11. While means is provided, in the provision of the spring 18, for absorbing vibration and checking the 100 tendency of the wedge to back away from its operative position, this is done with the sacrifice of but a small amount of friction surface between the two members of the anchor. The members of the anchor preferably engage rigidly with each other and with the base flange of the rail in such manner that considerable friction is developed and so that the cramping tendency of the device on the rail is fully effective. The 110

elastic engagement between the members is supplemental to the frictional engagement and is calculated particularly to absorb vibration which would otherwise have a tendency to loosen the frictional hold of one member upon the other. The spring 18 is preferably circular in shape or nearly so, and is formed so that one end will slide over the other when the spring is compressed. 5 By making the spring approximately circular it will roll when the wedge D is driven against it so that it does not appreciably resist the movement of the wedge. The purpose of this is to minimize the chance of the 10 spring breaking when the wedge is driven against it, which is much less likely to happen with a spring that can turn as the wedge goes forward thus eliminating friction.

While I have described my invention in a 20 certain preferred embodiment, it will be seen that modifications might be made without departure from the principles of the invention. The invention, for example, is applicable to other types of rail anchor than 25 the type herein shown and described, and obviously on anchors of the type shown the springs might be placed in the wedge instead of the jaw of the other member, although it is preferable to arrange it in the 30 jaw of the other member as there is more room and it is important that the spring, in whichever form used, be relatively heavy.

I claim:

1. In a rail anchor, the combination of a 35 member adapted to extend under a rail and provided at one end with means for engaging said rail and at the other with a jaw formed with a recess; a member interposed between said jaw and the rail, and an arcuate spring arranged in said recess so as to be compressed to less than its normal radius when said members are in operative position 40 on the rail.

2. In a rail anchor, the combination of a 45 member adapted to extend under a rail and provided at one end with means for engaging said rail and at the other with a jaw formed with a recess; a member interposed between said jaw and the rail, and a curved 50 spring with its ends overlapping each other which is arranged in said recess so as to bear against and be compressed by said last named member.

3. In a rail anchor, the combination of a 55 member adapted to extend under a rail and provided at one end with means for engaging said rail and at the other with a jaw formed with a recess; a wedge member interposed between said jaw and the rail, and 60 an arcuate spring arranged in said recess so as to be compressed to less than its normal radius when said members are in operative position on the rail.

4. In a rail anchor, the combination of a 65 member adapted to extend under a rail and

provided at one end with means for engaging said rail and at the other with a jaw formed with a recess; a wedge member interposed between said jaw and the rail; and a curved spring with its ends overlapping each other which is arranged in said recess so as to bear against and be compressed by 70 said last named member.

5. A rail anchor comprising two members engageable one with the other to provide 75 rail clamping means, and an arcuate spring interposed between said members which is compressed to less than its normal radius when the members are in operative position on the rail.

6. A rail anchor comprising two members engageable one with the other so as to provide rail clamping means, and a curved spring with its ends overlapped interposed 85 between said members so as to be compressed when said members are in operative position on the rail.

7. A rail anchor comprising two rail clamping members having contacting wedge faces, one of which faces is formed with a 90 recess, and an arcuate spring in said recess which is compressed to less than its normal radius when said members are in operative position on the rail.

8. A rail anchor comprising two rail 95 clamping members having contacting wedge faces, one of which faces is formed with a recess, and a curved spring, with its ends overlapped, arranged in said recess so as to be compressed when said members are in 100 operative position on the rail.

9. A rail anchor comprising a member adapted to extend under the base flange of a rail and formed on one end with a jaw 105 engaging one edge of said base flange and on the other with a jaw remote from the edge of the base flange, and a wedge member which is interposed between said last mentioned jaw and the rail; one of said members being formed with a recess, and a 110 curved spring with its ends overlapped arranged in said recess.

10. A rail anchor comprising a member adapted to extend under the base flange of a rail and formed on one end with a jaw 115 engaging one edge of said base flange and on the other with a jaw remote from the edge of the base flange, a wedge member which is interposed between said last mentioned jaw and the rail, one of said members being 120 formed with a recess, and an arcuate spring arranged in said recess which is compressed to less than its normal radius when said members are in operative position on the rail.

11. A rail anchor comprising a bar adapted to extend under the base flange of a rail formed on one end with a jaw to engage one edge of the base flange and on the other end with a jaw adapted to stand away from 125

- the edge of the rail, the inner vertical face of said jaw being formed with a recess, a tie abutting flange on said last mentioned jaw, a wedge member having a recess to engage the base flange of the rail and oppositely disposed thereto a wedge face to bear against the vertical inner face of said last named jaw, and a curved spring with its ends overlapping arranged in said recess.
- 10 12. A rail anchor comprising rail gripping members having a wedging relation with respect to each other, one of said members being formed with a recess, and a spring in said recess bearing against the other member which is compressed by the wedging action between said members and is also moved in said recess with the movement of said other member.
- 20 13. A rail anchor comprising rail gripping members having a wedging relation with respect to each other, one of said members being formed with a recess, and an arcuate spring in said recess bearing against the other member which is compressed by the wedging action between said members and is movable rotatably in said recess with the movement of said other member.
- 25 14. A rail anchor comprising rail gripping members having a wedging relation with respect to each other, one of said members being formed with a recess, and a spring
- in said recess bearing against the other member which is generally circular in form with its ends overlapped and is compressed by the wedging action between said members and is 35 rotatable in said recess with the movement of said other member.
- 15 15. A rail anchor comprising rail gripping members, one of which, in the application of the device to the rail, is movable with 40 respect to the other, and a spring interposed between said members which is compressed and moved bodily by the relative movement of one of said members with respect to the other.
- 25 16. A rail anchor comprising a member adapted to extend under the base flange of a rail and formed at one end with a jaw engaging one edge of said base flange and at the other end with a jaw remote from the 50 base flange which is formed with a recess, a wedge member interposed between said last mentioned jaw and the rail, and a spring generally circular in form, with its ends overlapping, arranged in said recess so that 55 it will rotate therein when the wedge member is driven into operative position.

EDWARD LAAS.
